UNITED STATES PATENT OFFICE.

FRANK L. SMITH, OF CHICAGO, ILLINOIS, ASSIGNOR OF TWO-THIRDS
TO ALVA C. RICKSECKER AND ONE-THIRD TO LEWIS A. NICHOLS,
OF CHICAGO, ILLINOIS.

VALVE.

No. 821,758.

Specification of Letters Patent.

Patented May 29, 1906.

Application filed July 18, 1904. Serial No. 216,935.

To all whom it may concern:

Be it known that I, FRANK L. SMITH, a citizen of the United States, residing at No. 215 East Sixty-fifth place, Chicago, in the county 5 of Cook and State of Illinois, have invented new and useful Improvements in Valves, of which the following is a specification, reference being had to the accompanying drawing, forming a part thereof.

10 The purpose of this invention is to provide an improved form of valve having a removable and interchangeable disk to afford its seating-face, and particularly an improved form of disk for such purpose.

15 It consists in the features of construction set out in the claims.

In the drawing the figure is an axial section of a valve embodying my invention, showing it in its seat, which is also in section.

20 The valve is shown with the conventional form of threaded stem 1, whose thread, it will be understood, is adapted to engage the casing of the valve for rotation in seating and unseating. Such stem is made rigid with 25 the head 2, such rigidity being feasible in view of the form of the seating-disk 3, which is an annular concavo-convex disk, which may be termed "spherical" in form, such spherical form adapting it to seat perfectly 30 on its tapered seat 4 in the valve-body (of which only the diaphragm containing the aperture and such tapered seat therein is shown) notwithstanding the plane of the diaphragm containing such seat may not be 35 strictly at right angles to the axis of the valve-stem. The concavo-convex annular seating-disk 3 is preferably made of relatively soft metal—such as copper, for example—so that it may not tend to cut or wear 40 the tapered seat 4, the wear being limited substantially to the valve-disk 3. This construction has the further advantage equally 45 important with that first named that the soft-metal disk accommodating itself to its seat in case of inaccurate adjustment in construction will not merely spring, which would tend to cause a buckling or curving inward at one part to compensate a curving outward at another part, but will yield without 50 materially springing and will come to its seat at all parts of the circumference. The necessary resistance for the work required of the valve under high pressures is afforded by the

arch construction involved in the spherical annular form of the disk, and further reinforcement is obtained when necessary by the relation of that form to the head 2, upon which it is mounted, which may be constructed as shown in the drawings—to wit, curved somewhat similarly to the disk, but 60 with its curvature such that the surface of the head facing the inner concave surface of the disk diverges from the said concave inner surface of the disk from a point near the back or upper edge of the disk toward the center, 65 leaving a cavity which in radial section is somewhat crescent-shaped. This interval, somewhat exaggerated in the drawing, is designed to correspond to the limit to which the disk may yield under pressure without 70 being ruptured or crimped—that is, taking into consideration its elasticity as well as its softness or flexibility and adaptation to yield to compression, so that while the disk may accommodate itself to the necessities 75 arising from inaccurate original adaptation to its seat to the full extent consistent with the integrity of the disk it shall be reinforced by the head from that limit and saved 80 from any destructive strain. It will be noticed that this annular spherical seating-disk is centered by its inner surface at the upper or rear periphery, fitting on the circular head, whose outer diameter at that point corresponds to the inner diameter of the disk. 85 The disk is also stopped at its rear upper edge by the annular flange 5 around the corresponding edge of the head, so that the compression on the seat may operate as described to produce an accommodation of the 90 disk to the seat and shall not merely force the disk back on the head. The direction of pressure in forcing the valve to its seat is such as does not ordinarily tend to spread the disk at its lodgment at the rear edge on 95 the flange 5; but for security in this respect it may be desirable in some cases to make this flange with its lower or forward surface at a slightly acute angle to the curved surface of the head, so that a slightly beveled or sharpened rear edge of the disk 3 will fit it with a tendency to thrust inward under pressure and defeat any tendency of the disk to spread 100 and so become dislodged from the flange.

The most convenient manner of securing 105 and binding the disk 3 to the valve-head is

that shown, wherein the head has a central threaded spud 6, which receives the clamping-nut 7.

It is preferable to flatten off the spherical reinforcing-boss of the head, so as to leave room under the disk or shell 3 for a gasket 8, which is bound tightly between the disk and head when the clamping-nut 7 is tightened up, and thereby there is prevented the possibility of leakage through the valve itself which might otherwise occur at the thread on which the nut is screwed and at the base of the disk 3, where it is stopped upon the flange 5 of the head.

15 The generic invention embodied in the construction shown in this application is also shown in another specific form in my Patent No. 749,637, dated January 12, 1904, for the reissue of which my application, Serial No. 20 217,275, filed July 19, 1904, is now pending, in which said application said generic invention is claimed broadly.

I claim—

1. A valve comprising a head and a removable metal concavo-convex annular disk 25 lodged on the head and supported thereon at the outer circumference with the convex surface outward and constituting the seating-face of the valve, the head being formed to 30 protrude into the concavity of said disk back of said outer seating-face for centering the disk on the head.

2. A valve comprising a head and a removable metal concavo-convex annular disk 35 approximately a spherical segment in form, the head being formed to protrude into the annular cavity of the disk and proximate the inner surface thereof back of or opposite the seating-face, and means for securing the disk 40 to the head.

3. A valve comprising a head and a removable metal disk having an annular concavo-convex portion whose convex surface 45 constitutes the seating-face of the valve, the valve-head being formed to approximately coincide with the concave inner surface of said disk opposite its said seating-face and to diverge slightly from the rear inner circumference for centering the disk on the head, the head having a marginal flange for posi-

tively supporting the disk, and means for binding the disk to the head.

4. A valve comprising a head and a removable metal disk having a concavo-convex annular portion whose outer surface constitutes the seating-face of the valve, the head being formed to protrude into the cavity of such concavo-convex portion to reinforce the disk and having a marginal flange for affording positive lodgment and support for the rear edge of the disk, the forward surface of said flange making an acute angle to the axis of the valve.

5. A valve comprising a head and a removable metal disk having a concavo-convex annular portion and a portion encompassed by such annular portion, said disk being supported at its outer circumference on the head and centered thereon with the convex face of the annulus outward and constituting the seating-face of the valve; means for clamping said encompassed portion of the disk to the head and a gasket interposed between the head and the disk at said clamped portion.

6. A valve comprising a head having a threaded post projecting from its face, a disk having a central aperture to receive said post, and having a valve-face, and having its outer edge seated on the face of the head, a gasket surrounding the post between the disk and head, and a nut on said post exterior of the disk.

7. A valve comprising a head having a threaded post projecting from its face, a disk having its outer edge seated on the face of the head, and having a central aperture to receive said post, and having an annular concavo-convex forming the valve-face, a nut on said post exterior of the disk, and means surrounding the post and adapted to prevent the passage of fluid through the aperture in the disk.

In testimony whereof I have hereunto set my hand, in the presence of two witnesses, at Chicago, Illinois, this 11th day of July, 1904. 95

FRANK L. SMITH.

In presence of—

CHAS. S. BURTON,
FRED. G. FISCHER.
